[57] CLAIM

The ornamental design for a winter weather footwear, as shown and described.

DESCRIPTION

FIG. 1 is a front elevational view of a winter weather footwear, showing our new design;

FIG. 2 is a rear elevational view thereof;

FIG. 3 is a right side elevational view thereof;

FIG. 4 is a left side elevational view thereof;

FIG. 5 is a right side and front perspective view thereof;

FIG. 6 is a bottom plan view thereof; and,

FIG. 7 is a top plan view thereof.

The inner portion of the shoe shown in broken lines is for illustrative purposes only and forms no part of the claimed design.
